ADJUSTING MEANS FOR GLUING MACHINES

Roland A. Page, New York, N. Y.

Application December 1, 1945, Serial No. 632,142

5 Claims. (Cl. 91—51)

1

The invention relates to adjusting mechanism for gluing machines, and particularly to the means for adjusting the doctor roll of such machines to and from the glue roll to thereby regulate the thickness of the layer or coating of glue carried by the glue roll.

In gluing machines of the character widely in use at the present time, the adjusting means for the doctor roll is so located that it is often very difficult to reach and adjust. Moreover, such adjusting means is often so positioned and arranged that its parts are exposed to the glue and soon become glue-covered, thus rendering the operation of the adjusting device difficult, if not impossible, with the result that such adjusting devices require repeated cleaning and constant care.

The present invention contemplates the provision of an adjusting device so arranged in respect to the doctor roll that the device is readily and conveniently available for manipulation and adjustment, whenever such adjustment is required. It further contemplates the provision of an adjusting device of this character so constructed that its movable or operating parts are enclosed in a suitable protective and enclosing housing, thus isolating them from the glue and eliminating the need for repeated cleaning of the adjusting means.

Still another object of the invention is to provide a simple, easily constructed, and sturdy device of this kind by which accurate adjustment of the doctor roll relative to the glue roll may be readily had by the mere turning of an adjustment screw that is conveniently located and readily operated.

These and other objects are attained by the invention, a more particular description of which will hereinafter appear and be set forth in the claims appended hereto.

Reference is to be had to the accompanying drawing, forming a part hereof, in which Fig. 1 is a longitudinal sectional view through an adjusting device for the doctor roll of a gluing machine, constructed in accordance with the invention; Fig. 2 is a top plan view of the same; Fig. 3 is a view looking at the under side of the housing of the adjusting mechanism; Fig. 4 is a side elevation, with parts in section, and on an enlarged scale, of the adjusting rod or stem and associated parts, and Fig. 5 is a view of the under side of the adjusting mechanism.

The improved adjusting means is applicable to various types of known gluing machines, most of which machines include a glue pot, a top portion

of which is shown at 1. The glue roll 2 rotates in such a position as to receive on its periphery, a coating of glue from the glue pot, for application to the article or material to be glued.

Various materials and articles require more or less glue, and to thus regulate the thickness of the coating of glue received on and applied by the roll 2, a so-called "doctor" roll 7 is employed, the same being adjusted to or from the periphery 10 of the glue roll 2 by the improved adjusting means to be described. The rolls 2 and 7 are driven from a suitable power source, by gearing or other drive means, not shown herein, since it is common in machines of this general character.

15 The glue roll 2 is provided with a shaft 3 rotatably mounted at its ends in bearing blocks 4, one of which is shown in Fig. 1. Each bearing block 4 is disposed in a recess 6 formed in the under side of a housing 5 secured to the top face of the plate or table portion 1 of the glue pot.

Provided in the under face of the housing 5 is a second recess 10 in which is received a slideable bearing block 9 carrying one end of the rotatable shaft 8 of the doctor roll 7, the other end of the shaft 8 being carried in a similar bearing block. Due to the fact that the blocks 9, at the opposite ends of the shaft 8, are slidably adjustable in their recesses 10 it will be obvious that by adjustment of the blocks 9 in the recess 10, the doctor roll 7 may be brought toward or away from the periphery of the glue roll 2. The means for securing such adjustment will now be described.

Forming a continuation of the recess 10 is an elongated recess portion 11 in which an adjusting stem or rod 15 is movable. Said stem or rod 15 has one end threaded as at 15a for reception within the internally threaded boss 14 of a head 12, secured to a face of the bearing block 9 by means of the screws 13 or other equivalent fastening means. The opposite end of the stem 15 is secured to an angular guide block 16 which closely fits, and is smoothly slideable, within the recess portion 11. The guide block 16 is formed with an inclined or angular face or end 17 which contacts with the end of an adjusting screw 18 threadably received in a threaded bore 19 extending slantingly or angularly through the body of the housing 5. The adjusting screw 18 has one end located on the outside of the housing 5 45 beyond a raised portion 21 formed on said housing, said end of the screw 18 being provided with a head 20 permitting manual rotation of the screw 18 to the required extent to adjust the doctor roll as desired.

Surrounding the stem 15 is a coil spring 22,

having one end bearing against the guide block 16 and its other end bearing against a washer 23 resting against a pair of spaced rib portions 24 projecting inwardly from the side walls 26 and 27 of the housing and between which the stem 15 is slidable. This arrangement is such that the coil spring 22 holds the guide block 16 in contact with the inner end of the adjusting screw 18 so that when the adjusting screw 18 is unthreaded, the spring will tend to draw the doctor roll 7 away from the glue roll 2 to the extent permitted by the screw 18. When the adjusting screw is threaded inwardly, or toward the guide block 16, its end operative against the inclined end 17 of the guide block 16, will force the stem 15 toward the right, to thus move the doctor roll 7 closer to the periphery of the glue roll 2. It will thus be obvious that by manually adjusting the screw 18, the doctor roll 7 can be moved to or from the glue roll 2 to the required extent to control the thickness of the layer or coating of glue carried and applied by the glue roll.

In carrying out the invention, it will be obvious that an adjusting device as above described will be provided at each end of the rolls 7 and 2, both adjusting devices being of similar construction.

It is to be noted that the recesses 6, 10 and 11 are each formed in the underside of the housing 1 and that the lower ends of these recesses are closed by the plate or table portion 1 when the housing is fastened down on the face of the plate portion 1. It will be further noted that the side walls 26 and 27 bounding the recess 11, make the recess 11 a completely closed one so that the adjusting apparatus is thus wholly enclosed and out of reach of the glue applied by the machine in connection with which this device is employed. The result of this arrangement is that the adjusting apparatus is always maintained in a clean and operative condition and seldom, if ever, requires dismantling for cleaning. Attention is also directed to the fact that the adjusting means arises from the top of the machine, and the head of the adjusting screw 18 is fully exposed and readily manually operative so that the adjustment of the doctor roll is simplicity itself. If desired, the exposed face of the projection 21 can be calibrated or graduated and the screw provided with a pointer or indicator so that repeated desired adjustment of the doctor roll can be readily secured by merely turning it to the required designations.

It will be apparent that while I have described the improved adjusting means for use in connection with a certain type of gluing machine it may readily, and with very slight modification, be applied to many types now known to the trade. Such modifications as are required to secure an application of the device to various types of machines are contemplated as being within the scope of the present invention and within the claims appended hereto.

What I claim is:

1. In a gluing machine, a housing provided with an elongated recess in its under face, a part of said recess being open at the sides, a block 70 slidable in the last-mentioned part of the recess, a stem projecting from the block, a spring surrounding the stem, an abutment in the recess against which one end of the spring rests, a head on one end of the stem, an adjustment screw

threaded through a part of the housing and operative against said head to thereby shift the stem axially against the pressure of the spring, the second end of the spring bearing against the head, and a doctor roll having one end of its shaft mounted in the block.

2. In a gluing machine as provided for in claim 1, wherein the abutment consists of spaced ribs on the side walls of the housing within the recess; the head on the stem has an angular surface against which one end of the adjustment screw contacts, and the adjustment screw extends slantingly through a threaded passage extending through the housing.

3. In a gluing machine, a base, an elongated housing member having a recessed under side directed toward the base, said housing member being secured to the base, a bearing block located in the recess in the housing member and confined between said housing member and the base, a doctor roll provided with a shaft having an end portion carried by the block, an extension carried by the block, and a threaded adjusting screw carried by the housing member and operative against said extension to move the block in one direction, and spring means tending to move the block in an opposite direction to an extent permitted by the adjusting screw.

4. In a gluing machine, a glue roll, a doctor roll adapted to be moved to and from the glue roll, means for moving said doctor roll toward the glue roll comprising an adjusting screw, supporting means for the doctor roll, a stem carried by said supporting means and having a head at one end against which the adjusting screw is operative, said screw being independent of the stem and a spring tending to hold the stem in contact with the adjusting screw.

5. In a gluing machine, a supporting surface, a housing having a recessed under face secured to said surface with the recessed face disposed against the surface, a bearing block confined in the recessed under face and between said face and the supporting surface, said bearing block being slidably mounted, a doctor roll having a shaft mounted in said bearing block, a boss secured to a face of said block, a stem having an end secured in said boss, a guide block, secured to the other end of the stem, said guide block having an inclined face, an adjustment screw threadably and slantingly extending through the housing and having an end entering the recess in the housing and bearing against the inclined face on the guide block, a coil spring surrounding the stem and having one end bearing against the guide block and tending to hold said guide block against the adjustment screw, and stop means in the recess serving as an abutment for the opposite end of the coil spring.
